METHOD OF FORMING CROSS-WOUND
PACKAGESCharles F. Beran, Tuckahoe, N. Y., assignor to
Celanese Corporation of America, a corporation
of Delaware

Application September 7, 1934, Serial No. 743,067

1 Claim. (CL 117—26)

This invention relates to a method and device for forming cross-wound packages having self supporting ends such as cheeses, cones, etc. and more particularly to cross-wound packages 5 that are uniform in twist and contain no ends of less twist than the bulk of the yarn.

An object of the invention is the economic and expeditious production of cross-wound packages in which the starting end of the thread or yarn 10 that contains practically no twist up to approximately the amount of twist desired is removed from the package without disturbing the solidity thereof. Other objects of the invention will appear from the following detailed description 15 and drawing.

In the drawing where like numbers refer to the same or similar elements:

Fig. 1 is an end elevation partially in section of a part of a take-up mechanism of a cheese winding device with the invention attached thereto.

Fig. 2 is a front elevation of a section of a take-up mechanism and is similar in location of parts to the section shown in Fig. 1.

Fig. 3 is a front view of an attachment for the cheese winding device shown in attached position in Figs. 1 and 2.

In the twisting and winding of thread it is customary to have a fastly rotating bobbin containing the yarn to be twisted and a take-up package driven slower than the bobbin, thus imparting twist to the yarn. The yarn is wound upon a core by the take-up device, guided thereto in a manner to crosswind the package by a reciprocating guide device. The yarn after leaving the bobbin traverses a space allowed for the ballooning of the yarn in the twisting action, and passes through guides, cleaners and possibly treating devices before reaching the take-up mechanism. For this reason and also because the machine as a whole or as a part has not reached the required speed and the formation of the balloon is not established, the first yard or first few yards of yarn coming to the take-up package 45 has not the same degree of twist as that imparted to the yarn after the operation has been completely started and balanced in speed. This length of yarn may be from a fraction to ten yards in length when working on high speed machines with low denier artificial filament yarns. Downward twisting devices are also employed in the art with the same results.

Formerly this length of yarn was taken up by the take-up package wound thereon in the same 55 manner as the yarn of the desired twist. In

warping, weaving, knitting and other textile operations this end of yarn would be fed to said devices and being of a different twist than the remaining yarn would result in a defect in the finished product. Further in unwinding the 5 yarn from the package this low twist end would draw the twist from several yards of yarn in an attempt to equalize itself which might amount to as much as ten yards of yarn that could not be used with safety.

By employing this invention this untwisted end 10 may be removed from the package leaving only yarn of equal twists thereon. This is done without materially increasing the work of the twisting machine operator or slowing up the process 15 whatsoever. Further, there is no weakening of the package or any drawing action that might cause tangling or sluffing of yarns on the end of the package.

According to my invention the untwisted or unprocessed end of the yarn is wound on the take-up package core at one end not regularly covered with yarn, then, when the delivery of twisted or processed yarn reaches the take-up package the yarn is automatically taken over by 25 the reciprocating guide and a package formed. The core with its package is then removed from the device and the ridge of yarn at the end, not a part of the main package, is wound or cut off and the end thus left free is tacked to the core 30 in a suitable manner. This invention is applicable to both the upward and downward twisting devices.

This invention is applicable to the winding of 35 twisted yarns of cotton, wool, real silk, flax, artificial yarns or the like wherein a cross-wound package, such as a cheese, or other like package is desired. The term "yarn" as employed in the specification and in the claim includes within its scope thread, assemblies or bundles of a number of continuous filaments which may be in parallel relationship or which may be twisted together, artificial bristles, straws, strips of foil, short lengths of staple fibres, or yarn spun from such staple fibres. The yarns may or may not 40 have been previously twisted, coated or otherwise processed.

Although this invention is applicable to any 45 type of yarn it is of particular applicability to yarns formed of substantially continuous filaments. The substantially continuous filaments may be formed in any suitable manner as by extruding a cellulose material in a liquid form through suitable orifices such as the manufacture of filaments containing reconstituted cellulose, 50 55

regenerated cellulose or organic derivatives of cellulose. Thus the filaments may contain such organic derivatives of cellulose as the organic esters of cellulose and cellulose ethers. Examples of organic esters of cellulose are cellulose acetate, cellulose formate, cellulose propionate and cellulose butyrate while examples of cellulose ethers are methyl cellulose, ethyl cellulose and benzyl cellulose.

10 The yarns may be twisted by any suitable mechanism such as those described in U. S. application 695,963 filed October 31, 1933, or more preferably by a device of the type described in U. S. application No. 742,108 filed August 30, 1934. In the drawing, wherein there is an illustration of one embodiment of the invention, those parts not directly related to the attachment have not been shown. However, reference may be made to the above application for details of the 20 general mechanism.

In the drawing 1 is a power driven shaft having mounted thereon a cylindrical roll 2 of metal or other suitable materials that may be suitably covered with a friction producing coating 3 such 25 as pressed cork, fibre mat, felt or the like.

A stationary shaft 4 may have mounted thereon an arm 5 having a split bearing 6 the pressure on which may be regulated by the screw 7. The shaft 4 is supported from the main frame of the 30 device. Mounted in the end of the arm 5 opposite its pivot is a shaft 8 that supports a core 9 upon which the take-up package is formed. The shaft 8 is held from rotation by a split bearing 10 held compressed by the screw 11. A handle 12 35 cooperates with means 13, which does not form part of the instant invention and which is shown in detail in application S. No. 742,108, filed August 30, 1934, for holding the core 9 against rotation relative to the shaft 8, and in operative 40 position to receive the yarn to be wound.

In operation, at the commencement the core 9 or if the operation has been started the wound yarn on the core 9 rests on the friction roller 3 and is rotated thereby at a constant peripheral 45 speed. As the package is being formed the yarn is guided to the package by a reciprocating guide 14 that is fastened or clipped to a reciprocating rod 15. This guide member is of the self threading type. The stroke of reciprocation of guide 14 50 is slightly less than the length of the core 9 such that the package is formed with from $\frac{1}{8}$ to $\frac{1}{2}$ inch of core projecting from each end of the package. For example, a popular size package may have a core $5\frac{1}{2}$ inches long while the 55 actual mass of yarn is only $4\frac{3}{4}$ inches long with $\frac{1}{2}$ inch of core protruding from one end. The core may be formed of pressed paper, cardboard, resin-fibre composition, molded resins, molded compounds of organic derivatives of cellulose or 60 similar material and is preferably formed with a yarn holding slot or notch 9' in one end for retaining and gripping the feed end of the yarn until the yarn has built up to a sufficient depth 65 not to slip on the core.

65 Mounted on the arm 5 and clamped in place by screw 11 is a bracket 16 having a depending section 17 containing an ear 18 on one side and a stud shaft 19 on the other side thereof. Mounted for rotation on the stud shaft 19 is a bearing member 20 having a slide bearing 21 therein adapted to slidably hold a shaft 22. The shaft 22 has fastened at one of its ends a pulley or grooved wheel 23 while the other end is threaded as at 24 for registry with a threaded hole in the ear 70 75 18. At the end of the threaded section 24 of

the shaft 22 is an abutment member 25 for preventing the shaft 22 from falling out of the slide bearing 21 when the same is in a vertical position.

In operation, the operator first secures the end of the yarn 26, in which a twist was inserted between the rotating spindle 28 and the pigtail guide 29, in the notch or slot 9' in the end 21 of the core 9 on which the yarn is to be wound. The core is then clamped on the device 13 and the yarn placed over the grooved wheel 23 with the threaded shaft 22 on which the wheel is mounted screwed into its innermost position in the ear 18. The core holding device is then lowered into place so that the core 9 rests on the friction roll 3 which causes the core to rotate and take up 10 the yarn. As the yarn is pulled over the grooved wheel 23, the wheel is caused to rotate by the friction of the yarn and this in turn unscrews the threaded shaft from the ear of the bracket. When the shaft is completely unscrewed, the unbalanced load of the wheel and yarn causes the wheel and shaft bearing to rotate on the bearing pivot 19 and fall out of engagement with the 15 yarn as shown in dotted lines in Fig. 3. After the yarn has fallen from the grooved wheel it lies in the path of reciprocating guide member 14 which is self threading and immediately picks up the yarn and guides it onto the core 9 to form a cross-wound package. The operator may as soon as the yarn is picked up by guide 14 20 return the bearing member to a position shown in full lines Fig. 3 and screw the shaft back into the ear 18 into the starting position ready for the next package.

In this manner the untwisted end of the yarn is wound upon the first section of the core which is usually a half inch in length. The amount of thread wrapped on this section will depend upon the diameter of wheel 23 and the pitch of the thread 24 on shaft 22 all of which may readily be varied to accomplish the desired length of feed not to be included in the finished package. The untwisted end of the yarn is thus wound on a normally exposed or naked section of the core in a completed package. The falling of the wheel 23 guides the yarn over to that section of the core traversed by the guide 14 so that it may be picked up by the guide 14 unaided by the operator.

When the package has been formed, the same 50 may be removed from the device by raising the arm 5 and releasing the core clamping means 13 after which the package may be easily slipped off and an empty core may then be inserted in the device. The package may consist of a solid well formed cheese of uniform yarn on a core and also a small ridge of windings on the normally naked end of the core. If desired the operator may strip this ridge of windings from the core having just sufficient yarn, to suit subsequent operations, to be reinserted in the notch of the core. This may be done by removing the original end of the yarn from the notch and pulling the windings undone or off from the package end, severing the yarn about a foot from where it 55 crosses in under the main package, rewinding the foot of yarn and hooking the new end in the notch. Or if desired, the operator may cut through all but the last few windings of the auxiliary package or ridge in a stroke lengthwise 60 the core allowing the severed part to fall off and then fasten the new end in the notch or slot of the core.

Although the above description is primarily directed to the twisting and winding of yarn it is 75

also generally applicable to any treatment or processing of yarn wherein the yarn is packaged into a cross-wound package such as a cone or a cheese or other package that has self supporting ends. Thus in applying size, lubricant, tints, dyes or other material to the yarn during a winding operation it may be desired not to include in the finished package the uniformly treated starting end that receives too little or too much treatment during threading of the device and the gaining of a speed in equilibrium with the treating means such that the yarn begins to come to the package with uniform treatment.

It is to be understood that the foregoing detailed description and drawing are merely given by way of illustration and many alterations may

be made therein without departing from the spirit of my invention.

Having described by invention, what I desire to secure by Letters Patent is:

Method of forming on a core a cross-wound package of uniformly twisted yarn, which comprises applying twist to the yarn while winding a predetermined length thereof on a part of the core normally left exposed, then, without interrupting the twisting and winding operations, proceeding with the winding so as to form a cross-wound package on that part of the core normally employed for the purpose and, thereafter, removing and discarding the predetermined length of yarn first wound on the core.

CHARLES F. BERAN.
